UNITED STATES PATENT OFFICE.

RYUJI SATO AND CHIYOSABURO MATSUI, OF NEW YORK, N. Y.

SWIMMING RACE.

1,424,038.

Specification of Letters Patent. Patented July 25, 1922.

Application filed January 3, 1921. Serial No. 434,664.

To all whom it may concern:

Be it known that we, RYUJI SATO and CHIYOSABURO MATSUI, subjects of the Emperor of Japan, residing at New York, in the county of New York and State of New York, have invented new and useful Improvements in Swimming Races, of which the following is a specification.

This invention relates to a mechanical swimming device or game for use at amusement parks and like places.

One of the objects is to provide a series of figures which are separately operable by manipulative means and provided with mechanism for giving an appearance of swimming to the figures as they are drawn through a tank of water.

Another object is to provide a device of this nature with independently operated means for intercepting the movement of the figures thereby offering hazards or obstructions.

Another object is to provide improved propelling means for the figures.

With these and other objects in view, which will be more apparent as the specification proceeds, the invention consists in certain novel construction and combination and arrangement of parts, the essential features of which are hereinafter fully described, are particularly pointed out in the appended claims, and are illustrated in the accompanying drawing in which:—

Figure 1 is a perspective view of our improved swimming race.

Figure 2 is a vertical sectional view taken transversely of Figure 1.

Figure 3 is an enlarged sectional view of the swimming figure, showing one of its postures in full line, and its other posture in dotted line.

Like characters of reference refer to like parts in all views.

Referring to the drawing in detail, 10 represents the tank which may be of any suitable material and may be made either of collapsible material or of rigid material as desired.

In the drawings only one swimmer and the controlling devices therefor are shown, it being understood that there are a plurality of such mounted in the tank and that all are exactly alike so that the description of the one applies to all.

Mounted on the bottom of the tank 10 is a pair of rails 11 which are preferably chan-

nel bars placed facing each other. Secured to one end of the tank and simulating a spring board, is a bracket 12 having a U-shaped aperture 13 in its free end. A movable platform 14 is supported upon wheels 15 riding in the channels of rails 11, said platform carrying a block 16 which normally stands in the aperture 13. The block 16 is cut away at 17 so as to provide an inclined surface 18 upon which the manikin, hereinafter described, rests when in swimming posture.

A manikin or figure 19 is provided with a downward extension of its feet which are pivoted in block 16 as at 20. The arms 21 of this manikin are mounted on the ends of a shaft 22 passing through the shoulders of the figure and having secured to it a pulley 23. An idler pulley 24 is also mounted in the figure 19 and a cord or wire 25 is secured to the tank at 26 and passes through an aperture 27 in surface 18, over idler 24 then about pulley 23, through an aperture 28 and out through the side of tank 10 at 29 to the operating mechanism, later described. It will, therefore, be seen that when line 25 is drawn out through aperture 29, the figure will be moved down onto surface 18 and the platform 14 will be drawn across the tank.

A pulley 30 is mounted in the manikin and over this passes a return cord 34 or wire the ends of which pass through apertures 31 and 32, respectively; and are attached to the tank 10 and a spring roller 33, respectively. When permitted to do so, the roller 33 will draw in line 34 thereby causing Figure 19 to rise to a standing posture, and the platform 14 to return to the spring board 12.

The line 25 after passing through the aperture 29 passes over a pulley 35 mounted on a spring 36, and thence over a pulley 37 and to a drum 38. This drum is loosely mounted on an upright rod 39 having at its upper end a hand wheel or manipulative member 40. Secured to shaft 39 is a sleeve 40^a carrying outstanding pins 41, and having a collar 42 above a control board 43. 105 Pins 41 are adapted to coact with pins 44 on drum 38 when the sleeve is in lowered position. Board 43 is supported by springs 45 and presses against the lower edge of boards 46 hinged to the framework 47 and 110 carrying cross bars 48 which are connected by rods 49 and normally moved to the right

22

by springs 50. A lever 51 is attached to one of the boards 46 and when moved counter-clockwise depresses all of the boards 46 and thereby the board 43 so that sleeve 40 is lowered until pins 41 and 44 are in clutch. A catch 52 holds the parts in this position until one of the figures completes its traverse of the tank at which time a suitable signal 53 may be operated and the catch 52 released by any suitable automatic means such as that shown in our copending application Serial No. 437,445, filed Jan. 15th, 1921.

Hazards or obstructions 54 in the form of sharks or other fanciful figures are provided in the path of the swimmer and are mounted on hinged supports 55 provided with springs 56 and lines 57 which are connected to cranks on a shaft 58 which may be either motor or hand driven. As shaft 58 is rotated the sharks are raised and lowered in front of the swimmer, spring 36 taking care of any undue tension on line 25 due to the obstructing of the movement of the swimmer. The skill and cunning of the operator is here called into play in not blocking movement of his manikin by trying to force it against the obstruction and in quickly passing over the obstruction as it is lowered. While we have described what is deemed to be the most desirable embodiment of our invention, it is obvious that many of the details may be varied without in any way departing from the spirit of our invention, and we therefore do not limit ourselves to the exact details of construction herein set forth nor to anything less than the whole of our invention limited only by the appended claims.

What is claimed as new is:—

1. A device of the class described, comprising a tank, a track mounted in said tank, a manikin mounted on said track, and means operable to draw said manikin along said

track and to cause said manikin to move 45 from erect to swimming posture and simulate swimming.

2. A device of the class described, comprising a tank, a track mounted in said tank, a manikin mounted on said track, and means 50 operable to draw said manikin along said track and to move said manikin from erect to swimming posture.

3. A device of the class described, comprising a tank, a track mounted in said tank, 55 a manikin mounted on said track, manipulative means to draw said manikin along said track from normal position and to move said manikin from standing to swimming posture, and automatic means to return said 60 manikin to normal position.

4. A device of the class described, comprising a tank, a track mounted in said tank, a manikin mounted on said track, means for moving said manikin along said track, hazards positively moved into the path of said manikin and resilient means for retracting said hazards.

5. A device of the class described, comprising a tank, a track mounted in said tank, 70 a manikin mounted on said track, means for moving said manikin along said track, hazards, means for positively moving said hazards in one direction independent of the moving means for said manikin, and resilient means for retracting said hazards.

6. A device of the class described comprising a tank, a track mounted in said tank, a manikin mounted on said track, means for moving said manikin along said track, hazards movable into and out of the path of movement of said manikin, and means for so moving said hazards.

In testimony whereof we have affixed our signatures.

RYUJI SATO.
CHIYOSABURO MATSUI.
